To all whom it may concern:

Be it known that I, Charles Morali, a citizen of the United States and resident of Forest Hills, in the county of Queens and State of New York, have invented a new, original, and ornamental Design for Shoes, of which the following is a specification, reference being had to the accompanying drawing, forming part thereof, in which:

Figure 2 is a perspective view of a shoe, showing my new design.

The dominant features of my invention com-

prise: the contrasting pattern over the quarter sections, the upper band of the pattern tapering to a width coincident with that of the ankle strap; the pattern of similar contrast over the toe; and the ornamental shirred bow at the forward edge of the throat.

I claim:

The ornamental design for a shoe, substantially as shown and described.

In witness whereof, I have signed my name this 26th day of August, 1935.

CHARLES MORALI.
